Primary Examiner — Cathron Brooks*Assistant Examiner* — Catherine Posthauer(74) *Attorney, Agent, or Firm* — Neugeboren O'Dowd PC(57) **CLAIM**

The ornamental design for a picture framing structure, as shown and described.

DESCRIPTION

FIG. 1 is an isometric front view of a picture framing structure.

FIG. 2 is a front view of the picture framing structure shown in FIG. 1.

FIG. 3 is a rear view of the picture framing structure shown in FIG. 1.

FIG. 4 is a side view of the picture framing structure shown in FIG. 1.

FIG. 5 is a side view of the picture framing structure shown in FIG. 1.

FIG. 6 is a top view of the picture framing structure shown in FIG. 1.

FIG. 7 is a bottom view of the picture framing structure shown in FIG. 1.

FIG. 8 is an isometric front view of a second embodiment of a picture framing structure.

FIG. 9 is a front view of the picture framing structure shown in FIG. 8; and,

FIG. 10 is a rear view of the picture framing structure shown in FIG. 8.

The broken lines showing portions of the picture framing structure form no part of the claimed design.
